UNITED STATES PATENT OFFICE.

HENRY DOBSON REESE, OF BILOXI, AND JOSEPH MARVIN HARLESS, OF GULFPORT, MISSISSIPPI, ASSIGNORS OF ONE-THIRD TO JOHN DEARING ODNEAL, OF GULFPORT, MISSISSIPPI.

EYE-TESTING MACHINE.

Application filed April 21, 1921. Serial No. 463,323.

To all whom it may concern:

Be it known that we, HENRY DOBSON REESE, of Biloxi, in the county of Harrison and State of Mississippi, and JOSEPH MARVIN HARLESS, of Gulfport, in the county of Harrison and State of Mississippi, both citizens of the United States, have invented certain new and useful Improvements in Eye-Testing Machines, of which the following is a 10 specification.

This invention relates to an eye testing machine.

The principal object of the invention is to provide a machine of the above character, 15 which is extremely simple in operation.

It is also an object of the invention to provide an eye testing machine which may be easily manipulated or operated by the person whose eyes are being tested.

20 It is a further object of the invention that the eye testing machine be incorporated with a cabinet so that the same can have an artistic housing.

Other objects and objects relating to details of construction, combination and arrangement of parts will hereinafter appear in the description to follow.

30 The invention is illustrated by way of example in the accompanying drawings, in which—

Figure 1 is a perspective view of a cabinet in which our eye testing machine is suitably housed.

Figure 2 is a detail elevation of the combined distance and character testing window, and also showing the operating mechanism therefor,

Figure 3 is a vertical section of the window shown in Figure 2 and showing the window in its raised position,

Figure 4 is a vertical sectional view taken substantially on the line 4—4 of Figure 5,

Figure 5 is a vertical sectional view taken substantially on the line 5—5 of Figure 1,

45 Figure 6 is an enlarged detail view illustrating the manner in which the lenses are mounted.

Referring to the drawings more particularly, A indicates generally the cabinet or housing of which 10 is the top, 11 the bottom, 12, the sides, 13 the front wall and 14 the rear wall. One of the sides is provided with a series of superimposed drawers as indicated at 15. Also a drawer 16 is provided in the bottom of the front wall 13, as

shown. A display rack 17 may also be suitably secured upon the front wall, as shown, if so desired. The interior surface of the front wall 13 is formed with a circular recess 18, said recess being enlarged about its edge as at 19. Centrally of the recess 18 there is journaled in the wall 13 a shaft 20, said shaft having its outer end journaled in the cross member 21 of the frame generally indicated at 22. The frame 22 extends from one side of the cabinet 10 to a central point thereof, the purpose of which will later become apparent. Upon the shaft 20 there is secured a sleeve or collar 23 by the means of a set screw 24, and upon the shaft there is positioned a disk wheel 25 which is held against movement upon the shaft by a washer plate indicated at 26, said washer plate being in turn secured against movement with respect to the shaft 20 by the means of a key, as shown. On the outer end of the shaft 20 there is secured a knurled nut 27 by which said shaft may be manually rotated. The outer edge of the disk wheel 25 is disposed in the enlarged portion 19 of the recess 18, as shown, and thus forming a space between the inner side of said wheel and the bottom of the recess 18.

In the disk wheel 25 there is provided a series of circumferentially spaced radial openings or slots 28, the outer ends of each slot terminating in a circular opening as at 29. Each of the openings 29 are adapted to receive an eye lens 30, said lenses being removably held in said openings by the means of a split spring ring as indicated at 31. The manner in which the spring rings 31 hold the lenses 30 in position is well known, and no detailed description will be here made. As is shown, the lenses 30 of each slot 28 form a pair which are equally spaced. The lenses placed in each pair are successively of greater or less degree of refraction, and the pairs are numbered in consecutive order, as shown.

In the wall 13 of the cabinet A there is provided a pair of spaced openings in which there is suitably mounted a pair of eye cups as indicated at 32, Figure 1. The interior of the cups 32 communicate with the openings in which they are mounted, and are so disposed that each of the pairs of the lenses 30 may be successively brought into alignment therewith.

110

In the rear wall 14 of the cabinet A there is provided an opening 33 which is in alignment with the eye cups 32. In the inner side edges of this opening there is provided 5 the grooves 34, and also in the top edge, a groove 35. In the bottom edge there is formed a recess 35', said recess being adapted to slidably accommodate a window frame 36 which is slidably mounted in the grooves 34. 10 The window frame 36 is slidably positioned in the grooves 34 for vertical movement, and in this frame there is carried a sheet of translucent material 37 upon which there is printed suitable testing sentences as shown 15 at 38. The sentences upon the sheet are written in large type at the top and gradually decrease in size of the type used as they proceed toward the bottom of the sheet, this being the general arrangement used for testing eyes.

Transversely of the cabinet A there extends a rod or shaft 39, said shaft having its one end journaled in the front wall 13, and its rear end in the rear wall 14. Upon 25 the rear end of the shaft 39 there is secured an arm 41, said arm being V-shaped as shown, and its outer end adapted to normally rest upon the ledge formed by the recess 35' and said arm being also adapted when swung 30 upwardly by the action of the shaft 39, to engage beneath the frame 36 and raise the same in a similar direction. The frame 36 is of course adapted to fall by its own gravity into its lowered position when not engaged by the arm 40. On the end of the arm projecting from the wall 13 there is secured a knurled nut 41 by which the shaft 39 may be rotated. Also there is secured on the shaft adjacent the nut 41 a pointer 42 and in 35 a dial alinement with said pointer there is printed on the wall 13, the words "Reading" and "Distance" as shown at 43 and 44, respectively. When the pointer assumes the position in alinement with the word "Reading" the window frame 36 will then be in 40 its raised position and close the opening 33, and when the pointer is in alinement with "Distance" the window frame 36 will then be lowered and the opening 33 unobstructed. 45 On the inner side of the front wall 13 there is pivotally mounted a lens frame 45 as indicated at 46, said frame being adapted to suitably support a pair of lenses as indicated at 47, and said lenses being in turn 50 held in position by spring rings similar to those shown for holding in position the lenses 30. The frame 45 is extended from its pivotal point as at 48, and at the outer end of this extension there is pivotally connected 55 a rod 49, said rod passing through the top 10 of the cabinet and terminating in a ring 50. By drawing the rod 50 upwardly the lenses 47 may be brought into registration with the eye cups 32. A suitable stop as 60 indicated at 51 is provided on the interior 65 of said housing in register with the opening

of the wall 13 to limit the downward movement of the lens frame 45.

It may be here added that the lenses mounted in the frame 45 are suitable for testing for stigmatism, that is, when used in 70 conjunction with a pair of the lenses 30.

In the operation of the present device, the person whose eyes are to be tested is seated before the front wall 13 of the cabinet so that he may look through the eye cups 32. The 75 wheel 25 is then rotated so that the number 4 would occur or would register with the opening 52 formed in the wall 13. When this occurs the pair of lenses 30 which are numbered 1, are in register with the eye 80 cups 32. This pair of lenses would be the initial and first test of the eyes. In case that these would prove to be too weak with respect to the degree of refraction the disk 25 may then be rotated so that the succeeding pair of lenses 30 would be brought into registration with the eye cups 32. The number which would register with the opening 52 in this case would then be 5. It is of course to be understood that when looking 90 through the eye cups 32 and the pair of lenses 30 which may be in register with said eye cups, that the opening 33 in the rear wall 14 is either closed or opened depending upon whether a distance test is to 95 be made or a reading test. The position of the frame 36 for closing the opening 33 would be indicated by the pointer 42. By manipulating or rotating the wheel 25 a person's eyes may be tested through a wide 100 range, either for distance or for reading.

In case the person whose eyes are being tested may show signs of stigmatism the frame 45 may then be swung downward into alinement with a pair of the lenses 30 and 105 the wheel 25 rotated as above described for bringing into alinement the different pairs of lenses 30. In this manner the exact degree of stigmatism may be determined.

While we have shown the preferred construction, combination and arrangement of our invention, it is to be understood however that we are aware of the fact that slight changes might be made by those skilled in the art without departing from the spirit of our 110 invention as indicated by the appended claims.

We claim:

1. An eye testing machine of the character described, comprising in combination, a 120 housing, a disk wheel rotatably mounted in said housing adjacent the front wall thereof, said disk having formed therein a plurality of circumferentially arranged radial openings, a pair of lenses mounted in each 125 of said openings and adapted to be successively brought into register with a pair of openings formed in the front wall of said housing, an opening formed in the rear wall 130 of said housing in register with the opening

in the front wall, a window frame slidable over said openings in the rear wall, a translucent panel carried by said window frame and means by which said window frame 5 may be raised and lowered from a position in front of the front wall of said housing.

2. An eye testing machine of the character described, comprising in combination, a housing, a disk wheel rotatably mounted in 10 said housing and positioned adjacent the front wall thereof, said disk wheel having formed therein a plurality of circumferentially arranged openings, a pair of lenses mounted in each of said openings adapted 15 to be successively brought into register with a pair of openings formed in the front wall of the housing and also with an opening in the rear wall of the housing in alignment with the pair of openings in the front wall 20 of the housing, removable translucent closure for the opening in the rear wall of the housing, and means operable from the front wall of the housing upon the exterior thereof whereby the translucent closure may be 25 caused to close the opening in the rear wall of the housing.

3. An eye testing machine of the character described, comprising in combination, a housing, a disk wheel rotatably supported 30 in said housing adjacent the front wall thereof, said disk wheel having formed therein a plurality of circumferentially arranged radial openings, a pair of lenses mounted in each of said openings and adapted 35 to be successively brought into register with a pair of openings in the front wall of the housing and also into register with an opening in the rear wall of the housing which is in alignment with the pair of open-

ings in the front wall of the housing, a 40 translucent panel for the opening in the rear wall of the housing adapted to be raised and lowered for opening and closing said opening, a rod extending between the front and rear walls of the housing, means for 45 manually rotating said rod from the front wall of the housing exterior thereof, and means connected with the rod whereby the translucent panel may be raised and lowered. 50

4. An eye testing machine of the character described, comprising in combination, a housing, a disk wheel rotatably supported in said housing adjacent the front wall thereof, said disk wheel having formed 55 therein a plurality of circumferentially arranged radial openings, a pair of lenses mounted in each of said openings and adapted to be successively brought into register with a pair of openings in the front wall of 60 the housing and also into register with an opening in the rear wall of the housing which is in alignment with the pair of openings in the front wall of the housing, a translucent panel for the openings in the 65 rear wall of the housing adapted to be raised and lowered for opening and closing said opening, a rod extending between the front and rear walls of the housing, means for manually rotating said rod from 70 the front wall of the housing exterior thereof, means connected with the rod whereby the translucent panel may be raised and lowered, and a dial and pointer associated with the rod whereby the position of the 75 translucent panel may be indicated.

HENRY DOBSON REESE.

JOSEPH MARVIN HARLESS.
